UNITED STATES PATENT OFFICE.

GEORGE KRAMER, OF SPOKANE, WASHINGTON.

AUTOMATIC CUT-OUT.

1,324,907.

Specification of Letters Patent. Patented Dec. 16, 1919.

Application filed May 23, 1918. Serial No. 236,130.

To all whom it may concern:

Be it known that I, GEORGE KRAMER, a citizen of the United States, residing at Spokane, in the county of Spokane and State 5 of Washington, have invented certain new and useful Improvements in Automatic Cut-Outs, of which the following is a specification.

The present invention relates to improvements in automatic cut-outs designed for use in connection with cable-ways of conveyors particularly applicable for use in coal handling plants where the coal is conveyed in buckets suspended from supporting cables 10 in railroad work, or coaling stations where the coal is conveyed to sorting bins, etc., and the cut-out is intended to shut off the current from a motor in the emergency of a broken or slack cable, or other defect. The 15 invention consists essentially in the operating mechanism combined with the switch in the electric power circuit whereby, under abnormal conditions, the operating mechanism is automatically actuated to open the 20 switch to break the circuit and thus shut off power from the motor.

In the accompanying drawings one complete example of the physical embodiment of the invention is illustrated, constructed 25 and arranged according to the best mode so far devised for the practical application of the principles of the invention. In addition to the preferred form of the applied invention, an added figure of drawing illustrates a modified form of application of the 30 invention to a switch board or switch in the controlling circuit of the power plant.

Figure 1 is a view, in front elevation of a switch and the operating mechanism of the 35 present invention applied thereto.

Fig. 2 is a view of the operating mechanism, at line 2-2 of Fig. 1.

Fig. 3 is a view of the switch, the housing in section, at line 3-3 of Fig. 1.

Fig. 4 is a view of a modified form of the connecting parts of the operating mechanism with the switch in the circuit of the 45 power plant.

In the preferred form of the invention as 50 illustrated in Figs. 1, 2 and 3, the housing 1, or box, is employed to inclose the switch, which is shown as of the usual "knife" type in which the pivoted blade or conductor 2 has a link 3 pivoted thereto, and by means 55 of a draw bar 4 and this link, the switch lever is connected with and actuated by the

rock bar 5 journaled at 6, 6 in the lower end of the housing, extending therethrough, and provided with an outer elongation or extension 5' which projects a sufficient distance from the housing to enable the operating mechanism to be connected therewith. The housing is supported on a suitable wall or surface, and the switch is electrically connected as usual in the power plant circuit 60 in which the motor is of course included. 65

The switch, when the power plant is being operated, is normally closed, and while a manually operated switch is illustrated in the drawing, such switch is, to all intents 70 and purposes, an automatic switch in its use with the present operating mechanism.

The switch is designed primarily to be opened when and if the two cables 7 and 8, or either of them, is slackened to a certain degree, provision being made to allow for slack to a limited degree without opening the switch. Upon the cables are supported the usual or standard type of carriers forming part of the conveying plant, but inasmuch as these carriers do not have a direct bearing upon the invention herein described, 75 they are omitted from the illustrations.

Upon each of the cables is supported a pulley or sheave, indicated by the numerals 80 9 and 10, these being idle pulleys that are journaled on the shaft 11 of a yoke 12, the shaft being of considerable length to enable the pulleys to shift laterally to compensate for and accommodate the movement of the cables as they may sway or swing laterally, as is usual. Each yoke has an arm as 13 or 14, pivoted at 15 to a suitable support, and thus adapted to swing vertically on this pivot, brackets 16 being 85 employed to support the pivots.

A rock lever 17, which is shown as a hand lever is fixed on the rock shaft 5, and this lever may be actuated from either or both of the pivoted arms 13 or 14 through the instrumentality of the long connecting rod 18 or the shorter connecting rod 19, the former connecting the upper lever arm 13 with the rock lever 17 and the latter connecting the lower arm 14 with the lever arm or rock 90 lever 17. The connection between the two rods and the lever arm however is not positive, as a slight lost motion is permitted, and to this end the lever arm or rock lever 17 is provided with a pair of transverse 95 sockets 20 through which these rods freely pass, but the rods have spaced heads 21,

above and below the rock lever, a predetermined distance, in order to permit a certain slack or movement of the suspending cables without movement to the rock lever, to compensate for unavoidable movements to the cables. If desired a weight, as 22 may be attached to the lever or rock lever 17 to aid in operating the switch lever by providing a balancing load for assisting in the pull on the lever to overcome friction.

From the above description, taken in connection with the drawings, it will readily be seen that if the cables, or either of them, should slacken or "dip" to an undesirable extent, due to obstruction to a bucket or carrier, or other parts of the apparatus becoming locked, the weighted rock lever 17 is swung downwardly on its pivot to such an extent as to rock the rock bar 5, and this motion, of course is transmitted to the switch lever 2 through the draw bar 4 and link 3, as readily understood. The switch may be closed again, by manual power, after the trouble has been remedied and the plant is again ready for operation.

In the modified form of switch in Fig. 4 the operating lever is designed to perform the function of a release latch 17' and when either of the two rods 18 or 19 is pushed down on this latch, the switch lever 23 is raised, and the circuit broken, by the spring 24. After the trouble has been remedied, the switch may be closed by pulling down on the handle 25 and the latch 17' is again caught over the lever 23 to hold it.

By the utilization of this device the necessity for an attendant at the motor ready

to shut it off is eliminated, as in case of slackening of the cables as before described, the motor is automatically shut off. A limited amount of side or lateral play is allowed for the cables by the employment of the long shaft for the pulleys, and, as before stated, a limited amount of vertical movement of the cables may be permitted before the operating mechanism acts to shut off the power.

Claims—

1. The combination with an electric switch and a rock bar operatively connected with the switch and having a lever arm, of a suspended cable and pulley thereon, a yoke provided with a comparatively long shaft for the pulley and a pivotal support for the yoke, a pendant connecting rod pivoted to the yoke, said lever having a socket therein and said rod passing through the socket and provided with spaced heads permitting a lost motion of the rod in its actuation of the lever.

2. The combination with an electric switch, its rock bar, and operating lever formed with sockets, of a pair of suspended cables, a pivoted yoke and laterally movable pulley for each cable, a pair of pendant connecting rods pivotally connected to the yokes and engaged in said sockets, said rods each having spaced heads permitting lost motion with relation to the lever, and a counterbalancing weight on the lever as described.

In testimony whereof I affix my signature.

GEORGE KRAMER.
